MODULATED WAVE SHAPER

De Witt Rugg Goddard, Riverhead, N. Y., assignor
to Radio Corporation of America, a corporation
of Delaware

Application February 28, 1945, Serial No. 580,211

8 Claims. (Cl. 250—36)

1

This invention relates to wave shaping circuit arrangements, and more particularly to a modulated wave shaper.

An object of my invention is to provide a modulated wave shaper which has a limiting action without loss of the amplitude modulation characteristic.

Another object is to provide means for squaring off the peaks of a modulated wave at varying amplitude levels thereby to produce an amplitude modulated wave which in some degree resembles a rectangular wave and is, therefore, rich in harmonics.

Still another object is to provide a low distortion harmonic generator suitable for deriving harmonics of a modulated wave which may be separated from the fundamental frequency components of such a wave.

The present invention has as an object, a method and means of overcoming certain difficulties encountered in the use of my MUSA system as described in U. S. application #695,893, filed September 10, 1946. In said application, the requirement is to produce harmonics of an amplitude modulated radio frequency signal. Ordinarily, if a radio frequency signal is subject to limiting so as to give a distorted form to the sine wave, this wave will be rich in harmonics. However, any normal form of limiting will, of course, remove amplitude modulation. In the present application, I disclose a special type of limiter which provides the distorted wave form rich in harmonics and yet preserves the amplitude modulation. In my multiple unit steerable antenna system, disclosure referred to above, it is necessary to use some harmonic of a fundamental frequency. An ordinary harmonic generator may be used for this purpose for on-off telegraphy phase modulation, frequency modulation, frequency shift keying and so forth but it is not satisfactory for amplitude modulated signals. The improved harmonic generator of the present invention is satisfactory for deriving harmonics of amplitude modulated signals without distorting the amplitude modulation. The essence of the invention itself resides in the novel construction of its circuit arrangement and in the method of wave shaping which is herein shown and described. It is sufficient, therefore, for the purposes of this specification to show how a modulated wave having the usual characteristics of a modulated sine wave may be applied as input energy to the circuit arrangement which I believe to be novel, and how this wave, after shaping, may be delivered to a plurality of band

2

pass filters for segregating the fundamental frequency components and one or more harmonic frequency components.

My invention will now be described in more detail, reference being made to the accompanying drawing in which

Fig. 1 shows a preferred circuit arrangement for carrying out the invention;

Fig. 2 shows graphically a representation of a modulated wave of ordinary sine wave formation;

Fig. 3 shows graphically a derivative of the wave illustrated in Fig. 2 but now shaped with substantially rectangular peaks, such a wave being well known to possess a richness of harmonics; and

Fig. 4 shows graphically a second harmonic derivative of the original wave.

Referring first to Fig. 1, I show therein two input terminals 1 across which the potentials of 20 a modulated wave such as shown in Fig. 2 may be impressed. One of the terminals 1 is directly connected to the control grid in an amplifier tube 2. The same terminal is also connected to one terminal of a potentiometer 3, the other terminal 25 of which is grounded. The second of the input terminals 1 is also grounded.

A detector tube 4 possesses a control grid which is directly connected to a tap on the potentiometer 3. By varying the position of the 30 tap on the potentiometer 3 the amplitude of the signals delivered in the output circuit of tube 4 may be varied with respect to the amplitude of corresponding signals delivered in the output circuit of the tube 2. In other respects, however, 35 the output current from tube 2 is characterized as a modulated radio frequency wave, while the output from tube 4 consists essentially in detected audio frequency components capable of being transformed in the audio frequency 40 former 6. Positive anode potentials are supplied to tubes 2 and 4 from any suitable source of direct current having a grounded negative terminal. The anode in tube 4 is coupled to ground through a radio frequency bypass condenser 12.

45 Connected to each of the cathodes in the tubes 2 and 4 are cathode resistors 8, each of which is shunted by a capacitor 9. The cathode circuit impedances are grounded.

50 In the output circuit of tube 2 I have included the primary winding of a radio frequency transformer 5, while in the output circuit of the tube 4 I have included the primary winding of a relatively low frequency transformer 6, suitable for 55 translating the modulation frequency compo-

ment of the signals with attenuation of the high frequency component.

Transformer 5 has a secondary winding the terminals of which are connected respectively to one and the other of two anodes in a twin diode rectifier tube 7. The two cathodes of this tube are inter-connected and are grounded.

A mid-tap on the secondary winding of transformer 5 is connected to the grounded cathodes of tube 7 through a resistor 10. This resistor is shunted by a capacitor 11. The mid-tap on the secondary of transformer 5 is also connected to one terminal of the secondary winding on transformer 6. The other terminal of the secondary on transformer 6 is connected to a tap on a potentiometer 13 which in turn is connected across the terminals of a biasing battery or other direct current source 14. The positive terminal of this source is grounded so that the anodes in tube 7 may be more or less negatively biased with respect to ground, thus rendering this tube unresponsive to signal currents below a certain critical amplitude level.

The anodes of tube 7 are connected respectively to two primary winding terminals on a transformer 21. The secondary winding of this transformer has a grounded center tap, and its terminals are connected respectively to one and the other of two control grids in a twin triode tube 15. The common cathode of tube 15 is connected to ground through a cathode resistor 16, this resistor being shunted by a capacitor 17.

Tube 15 is arranged to operate as a push-pull radio frequency amplifier. The two anodes are connected respectively to the terminals of a primary winding in a radio frequency output transformer 18. A mid-tap on the primary winding of transformer 18 is fed with direct current of suitable positive potential for operating the tube 15. The source of operating potential has a grounded negative terminal. The secondary winding of transformer 18 has its terminals connected to a plurality of radio frequency band pass filters such as 19 and 20. Additional filters may be supplied if desired. The band pass characteristics of these filters are so chosen as to provide at least a separation between the fundamental frequency output and the harmonic frequency output from the push-pull amplifier tube 15.

If separation is desired between harmonics of one order and harmonics of another order, such can readily be had by the use of additional band pass filters, as may be well understood by those skilled in the art.

The operation of my modulated wave shaper may be illustrated by considering that the input energy supplied to the terminals 1 is, for example, a modulated carrier wave having a carrier frequency of, say, 100 kilocycles. The signal passes to the amplifier 2 and detector 4. The output from tube 2 possesses both carrier frequency and modulation frequency components. The modulation frequency component from detector tube 4 is selected, the carrier wave component being substantially suppressed.

The variable potentials of the modulation wave as transformed through the transformer 6 are added algebraically to the D. C. bias potential of the tap on potentiometer 13, the resultant potential being impressed across the resistor 10 which produces a variable bias upon the anodes of the tube 7. The variations of bias are synchronized with the modulation amplitude variations detected in the twin diode tube 7.

The effect is, therefore, to clip the peaks of the waves applied to the push-pull amplifier 15 and to square them off. The variability of amplitude is, however, preserved.

As before stated, the output from the tube 15 will be recognized as one which is rich in harmonics and is, therefore, capable of utilization either for its harmonic frequency components or for purifying the fundamental frequency components which may be separated therefrom. The fundamental frequency characteristic of the output as passed through the band pass filter 20 would appear as shown in Fig. 3.

The band pass filter 19 may be so characterized as to deliver one or more selected harmonics. If, for example, the second harmonic alone is wanted, then its output would appear as graphically shown in Fig. 4.

It will be understood that modifications of my invention may be made by those skilled in the art without departing from the spirit and scope of the invention itself.

I claim:

1. In a signaling system the method of generating harmonic wave components of an amplitude modulated wave which comprises limiting the amplitudes of the wave peaks of the original wave, conforming the limited wave peaks to an envelope which simulates the modulation envelope of the original wave, and filtering the limited wave to separate said harmonic wave components from the fundamental frequency components thereof.

2. In apparatus of the class described, an electronic amplifier and an electronic detector, input circuits for said amplifier and detector connected to a common source of amplitude modulated waves, a full-wave rectifier stage coupled to the output side of said amplifier, said rectifier stage comprising a pair of diode discharge devices having independent anodes and interconnected cathodes, a single resistive impedance and divided coupling means forming a Y-connection between the cathodes and the anodes, and means for varying the potential gradient across said resistive impedance as a function of the output energy from said detector.

3. Apparatus according to claim 2 in combination with filtering means arranged and adapted to segregate in different channels the fundamental frequency components of said modulated waves and the harmonic frequency components thereof.

4. In a system for generating harmonic frequencies of varying amplitudes which conform substantially to the modulation envelope of a modulated fundamental frequency wave, a multi-stage translating circuit including an amplifier, and a twin diode detector, a transformer inter-coupling the output side of said amplifier and the input side of said detector, a resistor connecting a neutral tap on the secondary of said transformer with the two cathodes in said detector, the terminals of said secondary being separately connected to one and the other of the anodes in said detector, a capacitor in shunt with said resistor, a triode detector stage having an input circuit common to the input circuit of said amplifier, and means responsive to amplitude variations in the output from said triode detector for varying the potential gradient across said resistor, thereby to develop output waves from said twin diode detector which are rich in harmonics and which conform closely to the modulation envelope of the original wave.

5. A system according to claim 4 and including

parallel connected band pass filters for segregating different frequency components of the output energy derived from said twin diode detector, one of said filters being characterized for passing fundamental frequencies within a predetermined band and another of said filters being characterized for passing a predetermined band of harmonic frequencies.

6. The method of producing complex alternating current energy comprising components integrally related to a fundamental frequency including these steps, limiting the peak amplitudes of a first portion of amplitude varying wave energy of said fundamental frequency to derive wave energy of rectangular wave form, rectifying a second portion of said amplitude varying wave energy of said fundamental frequency, and modifying the first mentioned limiting action in accordance with the amplitude varying components derived by rectifying said second portion of wave energy to derive wave energy of rectangular wave form and of varying amplitude which is rich in harmonics.

7. The method of producing energies of frequencies integrally related to a fundamental frequency which includes these steps, limiting the peak amplitudes of a first portion of amplitude varying wave energy of said fundamental frequency to derive wave energy of rectangular wave form, rectifying a second portion of said amplitude varying wave energy of said fundamental frequency, modifying the first mentioned limiting action in accordance with the amplitude variations of said wave energy derived by rectifying the same to derive wave energy of rectangular wave form and varying amplitude which is rich in harmonics, and selectively separating energies

of the fundamental and harmonic frequencies appearing in said limited wave energy of varying amplitude as desired.

8. In apparatus of the class described, an electron discharge tube amplifier and an electron discharge tube detector, input circuits for said amplifier and detector coupled to a common source of amplitude varying wave energy, a third electron discharge tube having electrodes in an alternating current input circuit and in an alternating current output circuit, a coupling between the last input circuit and the output of said amplifier, a utilization circuit coupled with said alternating current output circuit, a biasing circuit for said third tube including a direct current impedance between electrodes thereof and a coupling between the output of said detector and said impedance.
